UNITED STATES PATENT OFFICE

CHARLES E. DAVIS, OF DAVENPORT, FLORIDA, ASSIGNEE TO GOODMAN MANUFACTURING COMPANY, OF CHICAGO, ILLINOIS, A CORPORATION OF ILLINOIS

APPARATUS FOR HANDLING LOOSE MATERIAL

Original application filed January 19, 1920, Serial No. 352,413. Divided and this application filed July 15, 1926, Serial No. 122,524. Renewed November 29, 1929.

This invention relates to an apparatus for handling loose material and has among other objects to provide a new and improved apparatus of this description for moving loose material from one place to another by means of a scraper, and for guiding, controlling and actuating the scraper during its operation. The device is particularly adapted for moving coal in a mine, but it is of course evident that it may be used for any other purpose.

This application is a division of my prior application, Serial Number 352,413, filed January 19, 1920.

15 The invention is illustrated in the accompanying drawings, wherein:

Figure 1 is a view showing a mine room with one form of device, embodying the invention;

20 Figure 2 is a vertical section through the mine room illustrated in Figure 1;

Figure 3 is an enlarged plan view with parts broken away showing the actuating mechanism for the head and tail lines of 25 the scraper;

Figure 4 is a side elevation of the construction illustrated in Figure 3;

Figure 5 is an enlarged view showing the brake mechanism for controlling the device 30 of Figures 3 and 4;

Figure 6 is a sectional view taken on line 6-6 of Figure 3;

Figure 7 is a sectional view through the controlling clutch mechanism for the actuating mechanism illustrated in Figure 3;

Figure 8 is a sectional view taken on line 8-8 of Figure 6; and

Figure 9 is a sectional view taken on line 9-9 of Figure 7.

40 Referring now to the drawings, I have shown a scraper 1 having a head line 2 connected therewith, and a tail line 3 also connected therewith. The tail line passes over a direction changing device 4 at the rear of 45 the scraper. Associated with the head line 2 is a direction changing device 5 which may be a pulley or any other form of direction changing device. This direction changing device is connected with a control line 6.

50 The control line passes about a direction

changing device 7. The direction changing devices 4 and 7 are preferably fixed in position. The control line and the head and tail lines are controlled from the same point by the same operator.

In the construction illustrated I provide a portable controlling mechanism for these lines. As illustrated this mechanism consists of a truck 8 provided with a pair of longitudinally spaced axles having supporting wheels 9, 9, thereon adapted to be run upon suitable tracks. When the device is in operation this truck may be run to the entrance of the mine room as illustrated in Figure 1. A short section of track 10 is placed on the floor and the truck is supported upon this track as illustrated in Figures 1 and 2. The truck is provided with a series of winding drums (see Figure 3).

These drums are driven by a suitable 70 motor which is here illustrated as an electric motor 14 and which is connected by the pinion 15 with the gear 16, mounted on the shaft 17 so as to rotate the shaft. The gear 16 is connected by a gear 18 with the shaft 19, so as to rotate said shaft. This shaft is provided with two clutches which as herein 75 shown are friction clutches, consisting of the members 20 and 21, which are loosely mounted on the shaft 19. Between these 80 members is a sliding sleeve 22 which has a groove 23 containing the members of a fork 24. An arm 25 is pivoted at 26 and is connected by a link 27^a with the fork 24. This arm 25 is pivoted to the control member 26^b. 85 The members 20 and 21 have the internal friction bands or pieces 27 (see Figures 7 and 9). One end of the band is connected at 27^a with the part 27^b rotating with the member. The other end of the band 27 is 90 connected to one end of the bell crank lever 27^c, which is pivoted to the part 27^b. The other end of the bell crank lever is connected by a link 28 with the sleeve 22. It will thus be seen that when the sleeve is moved to the 95 right (see Figure 7) the link 28 pulls down on the end of the bell crank lever 27^c, and rocks the bell crank lever to bring the ends of the clutch band closer together, and since the clutch band is on the inside of the wheel, 100

this releases the clutch. The movement to the right of the sleeve 22 straightens out the link 28 associated with the clutch wheel 20, and this lifts up the end of the bell crank lever 27 (see Figure 9) so as to separate the ends of the clutch band and cause it to press the inner face of the wheel, thus operatively connecting the wheel 20 with the shaft 19. The friction member of wheel 21 is operated to connect it with shaft 19 by moving the sleeve 22 to the left to straighten out link 28. The parts are arranged so that when the sleeve 22 is in an intermediate position neither friction clutch is set. Connected with the member 20 is a gear 29 and connected with the member 21 is a gear 30, these gears rotating when their associated members 20 and 21 rotate. The gear 30 is connected with a gear 31, loosely mounted on a shaft 32 and connected with a winding drum 33 about which the tail line 3 is wound. Mounted upon the shaft 32 is a clutch member 34 which may be of any desired form and which is herein shown as a toothed member adapted to engage teeth 35 on the gear 31. This clutch member is controlled by the lever 36. When the teeth 34 and 35 are engaging and the gear 31 is rotating the shaft 32 will also rotate. Mounted upon the shaft 32 is a drum 37 about which the control line 6 is wound. This drum is not directly connected with the shaft 32 but is provided with some means for permitting the shaft to rotate for a period without rotating the drum, and to then cause the drum to rotate.

In the construction shown the interior of the drum is provided with the threads 38. These threads engage threads on a nut 39 which is feathered to the shaft 32 by the feather 40. This nut is provided on opposite sides with the projections 41 and 42. When the nut is at the limit of its movement toward the right in Figure 6 the projection 42 engages a projection 43 on the part 44 attached to the drums 37, and when in this position the rotation of the shaft rotates the drum 37. When the nut 39 is at the limit of its movement to the left, the projection 41 engages a projection 45 and when in this position the rotation of the shaft also rotates the drum 37. In the intermediate position of the nut the rotation of the shaft does not rotate the drum. Some means is provided for holding the drum against rotation.

In the construction shown I have provided a brake for this purpose consisting of a brake wheel 46, having thereon a brake band 47 (see Figure 5). One end of this brake band is connected to the fixed part 48. The other end is connected to one end of a bell crank lever 49, pivoted at 50 to the frame. Some means is provided for moving this bell crank lever so as to clamp and unclamp the brake band. In the construc-

tion shown there is connected with the bell crank lever a link 51 which is connected with an arm 52 on the shaft 53, which shaft extends across the brake as shown in Figure 3, and is provided with cranks 54 by means of which it is rotated. It will be seen that when the shaft rotates so as to move the free end of the arm 52 to the left in Figure 5, the bell crank lever will be rocked to clamp the brake band upon the brake wheel, and when moved in the opposite direction to move the brake band from the brake wheel.

The truck 8 is provided with an incline chute or guide 56 for the scraper. Said chute is wide enough to accommodate a relatively large scraper, and the actuating mechanism for the scraper lines is compactly contained within the lateral boundaries of the chute. Control devices 26 and 54 for controlling the winding drums are accessible from either side of the chute, so that the operator may stand at either side where he is in view of the movements of the device and may also view the discharge of the scraper into the car at the other end of the device, and control the apparatus accordingly.

The truck is also provided with an extension arm 57 having a direction changing device 58 about which the head line 2 passes. This head line passes from the scraper about this direction changing device or pulley, and then passes about a pulley 59 to the drum 60 (see Figure 6). It will thus be seen that the head line is wound upon the drum 60 in a direction opposite to the direction about which the tail line is wound about the drum 33, so that as one lengthens the other shortens and vice-versa. The drum 60 is loosely mounted on the shaft 32 and has connection with the gear 61 which meshes with the gear 29 (see Figure 7). It will thus be seen that the drum for the head line is controlled by the friction clutch associated with the wheel 20 while the drum 33 for the tail line is controlled by the friction clutch associated with the wheel 21 and the drum 37 for the control line is dependent upon the drum for the tail line. The extension arm 57 is arranged so that it may be moved out of the way when the truck is being transported.

The use and operation of my invention is as follows:

When the device is to be used in a mine, the truck with the incline and control mechanism is run to the mouth of the room as illustrated in Figures 1 and 2 and is preferably placed on a short section of track 10. One of the cars 62 is then run in proximity to the outer end of the incline, and the direction changing devices 4 and 7 and the guide 63 then placed in position. The coal is mined from a wall 64 and is lying on the floor near this wall. The scraper is then brought to the position shown in full lines

in Figure 1. The operator starts the motor and throws in the friction clutch 20. This rotates the drum 60 which winds up the head line 2. The drum 33 is then free from the motor and the tail line 3 unwinds therefrom. The drum 37 upon which the control line is wound is held against rotation by the brake band on the wheel 46. The teeth of the clutch 34 of the drum for the tail line 10 are in engagement with the clutch teeth 35 on the gear 31, and hence as the tail line is unwound the shaft 32 is rotated. During this time the nut 39 associated with the control drum 37 is over at the right (see Figure 15 6), and hence the drum can be held against rotation by the brake, even though the shaft 32 is rotated, for this rotation of the shaft simply moves the nut 39 along toward the left.

20 The scraper 1 is an open mouth scraper having the head line connected by the branches 2^a with the two ends of the scraper. The pulling forward of the scraper causes it to be loaded with the loose coal. When 25 the scraper is full of coal it is then necessary to turn it so that it can be moved toward the entrance to the room. This turning must be gradual and this is done by allowing the direction changing device 5 to move away 30 from the direction changing device 7. In the present construction this is accomplished by loosening the brake band on the brake wheel 46. This permits the control line drum 37 to turn so that the control line 35 will be unwound therefrom, and direction changing device 5 moving away from the direction changing device 7 as shown in dotted lines in Figure 1, and hence there will be a gradual turning of the scraper.

40 It will be noted that in this particular construction the tail line drum and the control line drum are connected with the same shaft and that the control line drum instead of having a direct connection has a compensating connection. It will further be seen that during the first part of the movement of the scraper along the wall 64, the tail line drum 33 and the shaft 32 are being rotated because the tail line is being pulled 45 out or unwound, and that during this period the control line drum is held against rotation by the brake, the construction being such, however, that the shaft 32 is free to rotate, such rotation, however, causing the 50 nut 39 to move along the shaft 32, the nut being then disconnected from the driving connection with the drum. This disconnection is due to the projection 42 disengaging the projection 43. It will further be 55 seen that during the turning movement of the scraper the control line is unwound rapidly while the tail line is unwound slowly, and may in some instances not be unwound at all during this period because the scrap 60 65 1 is as it were turning about the direction changing device 4 as a pivot. This speeding up as it were of the control line drum causes it to move faster than the shaft 32 and moves the nut 39 again to the right, and when the projection 42 engages the projection 43 the shaft 32, the control line drum 37 and the tail line drum 33 then move in unison, such movement being caused by the pull upon the head line 2 due to its being wound upon the drum 60. The control line drum, it will thus be seen, first falls behind a certain amount and then speeds up to catch up the amount it fell behind, and it is therefore necessary to have an accurately timed mechanism for doing this, and the nut 39 and threads and associated parts provide such an accurate timing mechanism. The scraper is now pulled down by the head line to the incline or guide 56 and then is pulled up along said guide to the end thereof, and the material is discharged into the car 62, the scraper being open at the bottom and the end so that this discharge can easily take place. The operator stops the scraper at its discharge point. After the scraper has been unloaded it is moved back to its initial position as shown in full lines in Figure 1. This is done by disconnecting the friction member of wheel 20 and connecting the friction member of wheel 21 with said wheel so as to rotate the gear 28. This rotates the tail line drum so as to wind up the tail line and pull the scraper back. The head line drum 60 is free from the shaft so that it can rotate to unwind the head line. The control line drum 37 during this operation is connected with the shaft 32 by the projection 42 engaging the projection 43 (see Figure 6) so that the control line is wound on the drum.

105 It will be seen that in this construction I have combined in a self contained actuating or power element on truck 8, the three drums, one for the head line, another for the tail line, and the other for the control line, and that due to the peculiarities of movement of the system, the control line is, as it were, out of harmony because the unwinding of the control line is different from the winding of the head line and the unwinding of the tail line during a portion of the movement of the scraper.

110 The control line drum for example, during a part of the movement is slowed down or held against rotation while the shaft 32, the tail line drum 33 and the head line drum 60 are rotating, and hence the control line drum, as it were, falls behind. The brake is then released and the control line drum speeds up and rotates faster than the shaft 32 in order to make up for the time it was stopped or slowed down or retarded. In order to arrange for this lack of harmony or unison I have provided a compensating device consisting in the particular instance 115 120 125 130

of the nut 39 and the threads on the inside of the drum 37. This compensating device is properly timed so that the control line drum will make up just the amount it loses, and this timing or arrangement for properly making up the lost revolutions is done automatically, responsive to the pull of the head line. After the nut 39 reaches the point where the projection 42 engages the projection 43, the drums then rotate in unison. It is of course evident that the continued movement after the drum has speeded up, may be brought about even if the projection 42 is not in engagement with the projection 43, because the pull of the head line will insure unwinding of the drum 37 to bring about the proper unwinding of the control line.

In the normal operation of the device, the clutch 34 has its teeth in engagement with the teeth 35. If for example it is desired to move the direction changing devices 4 and 7 farther along, or for any reason to change the length of the various lines, then all that is necessary is to disconnect the clutch 34 whereupon the drums 33 and 37 may be turned independent of each other to wind or unwind the desired portion of the associated line so as to lengthen or shorten it. The drum 60 may also be turned independently of the other drums to shorten or lengthen the head line. Under these conditions the clutches 20 and 21 will of course be disconnected.

Although I have shown and described one form in which my invention may be embodied, it will be understood that the construction or arrangement of the various parts may be altered or varied without departing from the spirit and scope of the invention. Furthermore, I do not wish to be construed as limiting myself to the specific construction illustrated, excepting as it may be limited in the appended claims.

I claim as my invention:

1. A device for handling loose material comprising a scraper, a head line connected therewith, a tail line connected with said scraper, an actuating device connected with said head and tail line so as to act thereupon to move said scraper, a movable direction changing device engaging said head line so as to change its direction at a predetermined point during the first part of movement of the scraper, a control line connected with said movable direction changing device for controlling its position, said control line being connected with said actuating device, and means for rendering the connection between the control line and said actuating device inoperative during a portion of the time that the actuating device is acting upon the head line.

2. A device for handling loose material comprising a scraper, a head line connected

therewith, a tail line connected with said scraper, an actuating device connected with said head and tail line so as to act thereupon to move said scraper, a movable direction changing device engaging said head line so as to change its direction at a predetermined point during the first part of the movement of the scraper, a control line connected with said movable direction changing device for controlling its position, said control line being connected with said actuating device, and means for rendering the connection between the control line and said actuating device inoperative during a portion of the time that the actuating device is acting upon the head line and the tail line. 70

3. A device for handling loose material comprising a scraper, a head line connected therewith, a tail line connected with said scraper, a control line connected in said system for controlling the direction of movement of the scraper during a portion of its travel, an actuating device connected with said head and tail lines so as to act thereon to move said scraper, and a connection between said actuating device and said control line so that the said actuating device also acts upon said control line. 85

4. A device for handling loose material comprising a scraper, a head line connected therewith, a tail line connected with said scraper, a direction changing device for said head line adapted to change its direction at a predetermined point during the early part of the movement of the scraper, a control line connected with said direction changing device, a motor, a shaft driven by said motor, a winding drum for the head line and for the tail line connected with said shaft acting to lengthen and shorten the said head and tail lines when operated, an additional winding drum connected with said shaft for lengthening and shortening said control line, and means for rendering said latter winding drum inoperative during a portion of the rotation of said shaft. 100

5. A device for handling loose material comprising a scraper, a head line connected therewith, a tail line connected with said scraper, an actuating device connected with said head and tail line so as to act thereupon to move said scraper, a movable direction changing device engaging said head line so as to change its direction at a predetermined point during the first part of the movement of the scraper, a control line connected with said movable direction changing device for controlling its position, said control line being connected with said actuating device, and means for rendering the connection between the control line and said actuating device inoperative during a portion of the time that the actuating device is acting upon the head line and the tail line so as to retard the unwinding of the control line, 110

and means for automatically speeding up the unwinding of the control line after it has been retarded so as to compensate for such retardation.

6. A device for handling loose material comprising a scraper, a head line connected therewith, a tail line connected with said scraper, an actuating device connected with said head and tail line so as to act thereupon to move said scraper, a movable direction changing device engaging said head line so as to change its direction at a predetermined point during the first part of the movement of the scraper, a control line connected with said movable direction changing device for controlling its position, said control line being connected with said actuating device, and means for rendering the connection between the control line and said actuating device inoperative during a portion of the time that the actuating device is acting upon the head line and the tail line so as to retard the unwinding of the control line, and means for automatically speeding up the unwinding of the control line after it has been retarded so as to compensate for such retardation, said speeding up being responsive to the pull of the head line.

7. A device for handling loose material comprising a scraper, a head line connected therewith, a tail line connected with said scraped, an actuating mechanism adapted to be connected with said head line and said tail line so as to act thereon to move said scraper, a control line connected in said system, a connection between said control line and said actuating mechanism, and a compensating device interposed in said connection, said compensating device arranged so that the control line may be retarded and then speeded up so as to regain substantially the amount lost in the retardation.

8. A device for handling loose material comprising a scraper, a head line connected therewith, a tail line connected with said scraper, an actuating mechanism adapted to be connected with said head line and said tail line so as to act thereon to move said scraper, a control line connected in said system, a connection between said control line and said actuating mechanism, and a compensating device interposed in said connection, said compensating device arranged so that the control line may be retarded and then speeded up so as to regain substantially the amount lost in the retardation, the action of said compensating device being responsive to the pull of the head line.

9. A device for handling loose material comprising a scraper, a head line connected therewith, a tail line connected with said scraper, a direction changing device connected in said system, and a control line therefor, drums for said head line, tail line and control line, a motor, means for connect-

ing said drum with said motor, a compensating connection for said control line drum comprising a nut rotating with the shaft of said drum but slidable therealong, a thread connected with said drum and engaged by said nut, whereby the drum may rotate at a speed different from that of the shaft during a portion of the time.

10. A device for handling loose material comprising a scraper, a head line connected therewith, a tail line connected with said scraper, a direction changing device connected in said system, a control line therefor, drums for said head line, tail line and control line, a motor, means for connecting said drum with said motor, a compensating connection for said control line drum comprising a nut rotating with the shaft of said drum but slidable therealong, a thread connected with said drum and engaged by said nut, whereby the said drum may be rotated independently of the shaft by the pull of said head line, and means for connecting said nut with said shaft under predetermined conditions so that the shaft may rotate the drum.

Signed at Chicago, in the county of Cook and State of Illinois, this 13th day of July, A. D. 1926.

CHARLES E. DAVIS.
